DESIGN FOR A TOY FIRE ENGINE

Anthony N. Smith, Girard, Pa., assignor to The
Girard Model Works, Inc., Girard, Pa., a cor-
poration of Pennsylvania

Application August 21, 1933. Serial No. 49,076

Term of patent 7 years

To all whom it may concern:

Be it known that I, ANTHONY N. SMITH, a citizen of the United States, residing at Girard, in the county of Erie and State of Pennsylvania, have invented a new, original, and ornamental Design for a Toy Fire Engine, of which the following is a specification, reference being had to the accompanying drawing, in which—

Figure 1 is a side elevational view of a toy fire engine embodying my design;

Figure 2 is a top plan view;
Figure 3 is a bottom plan view;
Figure 4 is a front elevational view, and
Figure 5 is a rear elevational view.

I claim:

The ornamental design for a toy fire engine as shown.

In testimony of which I affix my signature.

ANTHONY N. SMITH.
